(57) **CLAIM**

The ornamental design for an display panel or screen with an animated graphical user interface, as shown and described.

DESCRIPTION

FIG. 1 is a front elevational view of a first image of an display panel or screen with an animated graphical user interface showing our new design;

FIG. 2 is a front elevational view of a second image thereof;

FIG. 3 is a front elevational view of a third image thereof;

FIG. 4 is a front elevational view of a fourth image thereof; and

FIG. 5 is a front elevational view of a fifth image thereof.

FIG. 6 is a front elevational view of a first image of a second embodiment of an display panel or screen with an animated graphical user interface showing our new design;

FIG. 7 is a front elevational view of a second image thereof;

FIG. 8 is a front elevational view of a third image thereof;

FIG. 9 is a front elevational view of a fourth image thereof; and,

FIG. 10 is a front elevational view of a fifth image thereof. The appearance of the image transitions sequentially between the images shown in FIGS. 1-5 and FIGS. 6-10. The process or period in which an image transitions to another forms no part of the claimed design.

The broken line showing of a display panel or screen, letter, text and other elements form no part of the claimed design.
